(57) **CLAIM**

The ornamental design for gripping member for a razor handle, as shown and described.

DESCRIPTION

FIG. 1 is a perspective view of a gripping member for a razor handle of the present invention;

FIG. 2 is a top view thereof;

FIG. 3 is bottom view thereof;

FIG. 4 is a right side elevational view thereof;

FIG. 5 is a left side elevational view thereof;

FIG. 6 is a rear thereof; and,

FIG. 7 is a front view thereof.

The broken lines immediately adjacent the solid contour lines of the gripping member define the bounds of the claimed design. All other broken lines are for illustrative purposes only. None of the broken lines form a part of the claimed design.
